SELF-CENTERING RELAY

Stuart K. Babcock, Northridge, Calif.

Application February 3, 1956, Serial No. 563,362

12 Claims. (Cl. 200—93)

My present invention relates to magnetically operated electrical relays, and it relates particularly to a magnetically operated relay which has an inherently powerful self-centering action, and which is therefore particularly adapted for "neutral-off" operation.

The conventional magnetically operated electrical relay includes only a single complete magnetic path and has an armature which is inactive until polarized by an electrical actuating current. This single magnetic path provides such a relatively small amount of mechanical power that it is difficult to obtain the required amount of sensitivity in the conventional relay.

Thus, using the conventional relay construction, it has heretofore been impossible to provide a very small relay which is highly sensitive. The only sensitive relays of conventional construction are relatively large and expensive, and hence are undesirable for many present uses which require small, sensitive relays, such as present electronic computers.

Conventional, relatively large relays which are sensitive must be closely adjusted because of the inadequate mechanical power provided by the single magnetic path. The resulting limited amount of movement available and the inadequate power provided by the single magnetic path are insufficient to close more than one contact at one time. However, it is often desirable to close two contacts at once.

The conventional relay is not inherently self-centering, and hence must be provided with a suitable spring to become self-centering. Overcoming the spring tension in these conventional self-centering relays causes them to be even less sensitive than they would otherwise be. Such spring-actuated self-centering relays have very close tolerances and difficult adjustments, and are relatively large and expensive.

Since most electronic equipment operates through magnetically operated electrical relays, the above-described inadequacies in conventional prior art relays have seriously hampered the development and effectiveness of electronic equipment.

It is therefore an object of my present invention to provide a magnetically operated electrical relay which operates on a completely new principle of operation from conventional magnetically operated relays. This new principle of operation consists of establishing a balanced condition between adjacent magnets with like poles opposing and hence repelling one another, and then upsetting this balanced condition by applying an additional magnetism to a central region of at least one of the balanced magnets to increase the magnetic strength at one pole of that magnet and decrease the magnetic strength of the other pole of that magnet.

My preferred embodiment consists of three parallel magnets with like poles at the same ends and with the center magnet being pivotal. The side magnets are magnetically associated, at their central regions, with electromagnets which may cooperate in operation to assist one another giving a maximum of mechanical power to

2

the central, pivoted magnet, or which may alternatively oppose one another in operation to provide a differential power output at the central, pivotal magnet.

Another object of my present invention is to provide a magnetically operated electrical relay which employs a plurality of separate magnetic paths, preferably four (4) in number, all of which operate cumulatively to produce mechanical power in the relay.

Another object of my present invention is to provide a magnetically operated electrical relay having sufficient mechanical power to permit a relatively small relay to be relatively sensitive.

Another object of my present invention is to provide a magnetically operated electrical relay having sufficient mechanical power to permit a relatively large amount of mechanical movement, whereby close adjustments are eliminated.

Another object of my present invention is to provide a magnetically operated electrical relay having sufficient mechanical power and movement to permit a plurality of contacts to be closed at the same time.

Another object of my present invention is to provide a magnetically operated electrical relay which is inherently automatically self-centering without requiring a centering spring, and which is inherently always in perfect balance when in the centered position.

Another object of my present invention is to provide a magnetically operated electrical relay which is inherently highly sensitive, and which is therefore inherently uncomplicated as to manufacturing tolerances, bearing accuracy and the like, rendering the relay very inexpensive to manufacture.

Another object of my present invention is to provide a magnetically operated electrical relay of the character described which, being inherently self-centering, is particularly adapted for "neutral-off" operation.

Another object of my invention is to provide a magnetically operated electrical relay which may be so electrically connected as to mechanically reflect an electrical differential, thus providing a true differential relay.

Another object of my present invention is to provide a magnetically operated electrical relay which may be made both small and highly sensitive, and which may therefore be actuated by small, inexpensive transistors.

Other objects and advantages of my present invention will be apparent from the following description and claims, the novelty of my invention consisting in the features of construction, the combinations of parts, the novel relations of the members and the relative proportioning, disposition and operation thereof, all as is more completely described herein and as is more particularly pointed out in the appended claims.

In the accompanying drawings, forming a part of my present specification:

55 Figure 1 is a perspective view of my completely assembled relay with the armature in its normal, centered position.

Figure 2 is a vertical section along the line 2—2 in Figure 1.

60 Figure 3 is a top plan view of my relay actuated so that the armature is rotated anti-clockwise.

Figure 4 is a top plan view of my relay similar to Figure 3 with the relay actuated so that the armature is rotated clockwise.

65 Figure 5 is a schematic diagram of my relay illustrating my completely new mode of operation.

My relay 10 is provided with a flat base or yoke 12 upon which is mounted an upwardly directed boss 14 that is integrally attached to the center of base member 12 by a rivet 16 or by other conventional means.

70 A bearing hole 18 extends downwardly from the top of boss 14, terminating in a flat bearing surface 20.

The armature 22 of my relay 10 consists principally of a single permanent magnet 24 having an integral spindle 26 depending from its center. Spindle 26 is provided with a sharply pointed lower end 28, whereby armature 22 is pivotally mounted with spindle 26 disposed within bearing hole 18, and with the pointed lower end 28 of spindle 26 bearing against the flat bearing surface 20.

A pair of electromagnets 30 and 32 are integrally connected to base member 12 near the respective ends of base member 12, and extend upwardly from base member 12. Electromagnets 30 and 32 include respective core members 34 and 36, and respective coil members 38 and 40 of conventional construction.

The upper ends of core members 34 and 36 are bent inwardly toward the pivotally mounted armature 22, and permanent magnets 42 and 44 are integrally attached to the upper ends of the respective core members 34 and 36. The upper ends of core members 34 and 36 are joined to the respective permanent magnets 42 and 44 at substantially the magnetic and mechanical centers of the respective permanent magnets 42 and 44. The magnetic and mechanical centers are at the same point along the length of such a permanent magnet.

Permanent magnets 42 and 44 are disposed substantially parallel to one another, and are spaced apart sufficiently to permit a substantial amount of pivoting movement of armature magnet 24. Permanent magnets 42 and 44 are substantially equidistant from armature magnet 24 on opposite sides of armature magnet 24, and all three of the magnets 24, 42 and 44 are disposed in substantially the same plane, which is a plane substantially perpendicular to boss 14 and armature spindle 26.

A contact point base member 46 is integrally attached to boss 14, and is composed of a suitable electrical insulator. In the embodiment of my invention illustrated in the drawings there are four (4) contact points, two (2) of the contact points, 48 and 50, being disposed on the same side of boss 14 as electromagnet 30, and the other two (2) contact points, 52 and 54, being disposed on the same side of boss 14 as electromagnet 32.

Contact points 48, 50, 52 and 54 are disposed substantially below the permanent magnet 24 of armature 22 to permit a pair of contact fingers 56 and 58 integral with armature magnet 24 and depending below armature magnet 24 to be disposed between the respective opposing pairs of contact points. Thus, one depending contact finger 56 extends downwardly to a position between the opposing contact points 48 and 52, while the other depending contact finger 58 extends downwardly below armature magnet 24 to a position between the opposing contact points 50 and 54.

Depending contact fingers 56 and 58 are preferably somewhat flexible and resilient, and although I have shown them as being substantially square in cross-section, it is to be understood that they may consist of conventional round wire members. Presently preferred contact fingers 56 and 58 consist of beryllium-copper wire which is rhodium plated.

A presently preferred material of which the permanent magnets 24, 42 and 44 are composed, is well known in the trade as "Alnico 4," although any other suitable permanent magnet material may be used. It would also be possible to substitute electromagnets for the permanent magnets 24, 42 and 44, but this would have the disadvantages of unduly complicating the structure and of adding to the bulk of the structure.

A presently preferred sub-miniature embodiment of my invention which is highly sensitive utilizes electromagnet coil members 38 and 40 each having a resistance of substantially 1500 ohms resistance.

By the construction heretofore described and shown in the drawings, I am able to provide a sub-miniature relay that is highly sensitive and operable at approximately 1 milliampere at approximately 3 volts, thus requiring

only approximately 3 milliwatts of power. Such a sub-miniature relay constructed in accordance with my present invention weighs less than one quarter of an ounce.

Referring now to Figure 5 of the drawings, I have there shown a schematic diagram of my present invention in which I have included a battery or other source of direct current 58 which is operatively connected to the electromagnet coil members 38 and 40 through a double pole, double throw switch 62. In Figure 5 of the drawings I have arranged the electromagnet coil members 38 and 40 in series winding relationship, which is my preferred winding relationship for normal operation of the device, causing all four (4) of the magnetic paths to cooperate in operation to assist one another, getting the maximum mechanical power.

The three permanent magnets, 24, 42 and 44, are all disposed in parallel relationship in the unactuated condition of the relay. By orienting magnets 42, 44 and 24 so that like poles are at the same ends of the magnets, both of the side magnets 42 and 44 will repel center magnet 24 at both ends of center magnet 24, causing center magnet 24 to become self-centered in direct alignment with the side magnets 42 and 44 as shown in Figure 5.

This self-centering action requires no springs, and is very powerful, with four (4) magnetic paths holding center magnet 24 against rotation.

Actuation of switch 62 to energize electromagnets 30 and 32 to cause the end of electromagnet 30 that connects with permanent magnet 42 to become a north pole, and to correspondingly cause the end of electromagnet 32 that connects with permanent magnet 44 to become a south pole, will cause central magnet 24 to rotate anti-clockwise to the position shown in Figure 3. This rotation will be effected by the cumulative action of all four (4) of the magnetic paths. The north polarity of electromagnet 30 will assist the north polarity at the upper end of permanent magnet 42 in Figure 5 to increase the repulsive force between the upper ends of magnets 42 and 24, causing an anti-clockwise force to operate on center magnet 24. Conversely, the north polarity of electromagnet 30 will diminish the south polarity of the lower end of magnet 42, thus greatly amplifying the anti-clockwise torque on center magnet 24 provided by the repulsion of the north pole upper ends of magnets 42 and 24.

The south polarity of electromagnet 32 increases the strength of the south pole, lower end of magnet 44, thus increasing the repulsion between the south pole lower end of magnet 44 and the south pole lower end of pivotal magnet 24, thus further increasing the anti-clockwise torque on the center magnet 24. Conversely, the south pole of electromagnet 32 decreases the strength of the north pole at the upper end of magnet 44, thus decreasing the repulsion between the upper ends of magnets 44 and 24, further increasing the repulsive effect of the opposing south poles at the bottoms of magnets 44 and 24, thus further increasing the anti-clockwise torque on center magnet 24.

Since the repulsive effect of like magnetic poles decreases according to the square of the distance between the poles, it will be obvious that upon energizing electromagnets 30 and 32 in the aforesaid manner, pivotal magnet 24 will rotate anti-clockwise to a stable position short of actual physical contact between pivotal magnet 24 and the stationary magnets 42 and 44. However, a relatively small amount of electrical power is required in electromagnets 32 and 30 to cause a relatively large mechanical displacement of the pivotal magnet 24, thus rendering this relay a highly sensitive one.

The above-described anti-clockwise rotation of pivotal magnet 24 will cause contact finger 56 to meet contact point 48, and will cause contact finger 58 to meet contact point 54, thus providing electrical communication between contact points 54 and 48.

It will be obvious from the above-described anti-clockwise operation of pivotal magnet 24 that when switch 62 is reversed, causing electromagnet 30 to assume a south polarity adjacent to fixed magnet 42, and causing electromagnet 32 to assume a north polarity adjacent to fixed magnet 44, the reverse operation will be effected, causing pivotal magnet 24 to rotate clockwise to the position shown in Figure 4. This will cause contact finger 58 to engage contact point 50, and will cause contact finger 56 to engage contact point 52, thus providing electrical communication between contact points 50 and 52.

Although I have shown electromagnets 30 and 32 as being wired in series in Figure 5, electromagnets 30 and 32 may alternatively be actuated independently of one another to provide a true differential relay. In that case, both leads of each electromagnet, 30 and 32, are brought out, and one of the two electrical potentials to be compared is applied across electromagnet 30, while the other electrical potential to be compared is applied across electromagnet 32, with these two potentials to be compared being applied to electromagnets 30 and 32 so as to produce opposing polarities rather than assisting polarities in electromagnets 30 and 32.

For example, if both potentials are in the same direction, such as positive, the same polarity will be assumed by both electromagnets 30 and 32 adjacent to their respective fixed magnets 42 and 44. When the two potentials are equal, the strength of electromagnets 30 and 32 will be equal, whereby pivotal magnet 24 will remain absolutely centered. When one potential becomes larger than the other, the pivotal magnet 24 will rotate in a corresponding direction an amount corresponding to the difference in potential, and when the potentials are reversed the pivotal magnet 24 will reverse in direction.

Although I have shown and described my present invention with four (4) contact points, 48, 50, 52 and 54, and with two (2) cooperating contact fingers 56 and 58 depending from the armature magnet 24, it will be obvious that any switching combination can be provided in my relay. For example, my relay may be provided as a single pole, single or double throw switch, or may be provided as a double pole, single or double throw switch.

A presently preferred form of single pole, double throw switch utilizes a pair of depending contact fingers 56 and 58, with only a single pair of contact points 48 and 50 on one side of the armature 22. In this arrangement, a fine, flexible conducting wire is integrally connected to spindle 26 to provide current to the contact fingers 56 and 58.

My new structure consisting of a plurality of aligned magnets with like poles at the same ends, and with one of the magnets being pivoted, and with electromagnets being applied to the centers of the un-pivoted magnets, results in a new mode of operation and new and beneficial results which are so surprising that they completely overcome most of the difficulties intrinsic in conventional prior art relays.

Thus, my new relay has a strong self-centering action, and is therefore particularly adapted for "neutral-off" operation, without requiring any springs whatsoever.

The plurality of separate magnetic paths, preferably four (4), provide greatly increased mechanical power over conventional prior art relays. This provides a high degree of sensitivity, and permits my relays to be constructed very small, while still retaining high sensitivity. This also eliminates close tolerance problems, simplifying manufacturing procedures.

The large amounts of mechanical movement available in my present invention, coupled with the increased power, eliminate the necessity for difficult and close adjustments, and permit a plurality of contacts to be closed simultaneously.

My present invention has the additional inherent advantage that it is particularly adaptable as a true differ-

ential relay to compare two separate electrical potentials.

The simplicity and completely uncritical nature of my present relay make it far more dependable than conventional prior art relays, and of course, the strong self-centering action and great mechanical power inherent in my relay are important factors in this reliability.

The small power requirements of my present relay make it particularly adaptable for use in connection with transistors.

10 It is to be understood that the form of my invention herein shown and described is my preferred embodiment and that various changes in the shape, size and arrangement of parts may be resorted to without departing from the spirit of my invention, or the scope of my appended claims.

I claim:

1. An electric current responsive device including a pivoted permanent magnet pivoted at a point intermediate its two poles, a stationary permanent magnet disposed adjacent to said pivoted magnet, like poles of said pivoted and stationary magnets being disposed adjacent to each other in repelling relation, and an electromagnet having one pole magnetically connected with said stationary magnet intermediate its two poles.

2. An electric current responsive device including a pivoted permanent magnet pivoted at a point intermediate its two poles, a pair of stationary permanent magnets disposed on opposite sides of said pivoted magnet, like poles of said pivoted and stationary magnets being disposed adjacent to each other in repelling relation, and an electromagnet pole magnetically connected with each of said stationary magnets intermediate its two poles.

3. An electric current responsive device including a pivoted permanent magnet pivoted at a point intermediate its two poles, a pair of stationary permanent magnets disposed on opposite sides of said pivoted magnet, like poles of said pivoted and stationary magnets being disposed adjacent to each other in repelling relation, and an electromagnet pole of one polarity magnetically connected to one of said stationary magnets intermediate its two poles and an electromagnet pole of the opposite polarity magnetically connected to the other of said stationary magnets intermediate its two poles.

4. A magnetic force actuated device including a pivoted permanent magnet pivoted at a point intermediate its two poles, a pair of stationary permanent magnets disposed on opposite sides of said pivoted magnet, like poles of said pivoted and stationary magnets being disposed adjacent to each other in repelling relation, and selective means for substantially simultaneously applying a magnetic force of one polarity to one of said stationary magnets intermediate of its two poles and a magnetic force of the opposite polarity to the other of said stationary magnets intermediate of its two poles.

5. A magnetic force responsive device including a pivoted permanent bar magnet pivoted at a point intermediate its two poles, a pair of substantially parallel stationary permanent bar magnets disposed in substantially the same plane as said pivoted magnet, like poles of said pivoted and stationary magnets being disposed adjacent to each other in repelling relation, the pivoting axis of said pivoted magnet being substantially perpendicular to said plane, and selective means for substantially simultaneously applying a magnetic force of one polarity to one of said stationary magnets intermediate its two poles and a magnetic force of the opposite polarity to the other of said stationary magnets intermediate of its two poles.

6. An electric current actuated relay including a pivoted permanent magnet pivoted at a point intermediate its two poles, a stationary permanent magnet disposed adjacent to said pivoted magnet, like poles of said pivoted and stationary magnets being disposed adjacent to each other in repelling relation, an electromagnet having one pole magnetically connected with one of said pivoted

and stationary magnets intermediate its two poles, a stationary electrical contact member, and a movable electrical contact member operatively connected to said pivoted magnet and selectively operatively engageable with said stationary contact member according to the pivotal position of said pivoted magnet.

7. An electric current actuated relay including a pivoted permanent magnet pivoted at a point intermediate its two poles, a stationary permanent magnet disposed adjacent to said pivoted magnet, like poles of said pivoted and stationary magnets being disposed adjacent to each other in repelling relation, an electromagnet having one pole magnetically connected with said stationary magnet intermediate its two poles, a stationary electrical contact member, and a movable electrical contact member operatively connected to said movable magnet and selectively engageable with said stationary contact member according to the pivotal position of said pivoted magnet.

8. An electric current actuated relay including a pivoted permanent magnet pivoted at a point intermediate its two poles, a pair of stationary permanent magnets disposed on opposite sides of said pivoted magnet, like poles of said pivoted and stationary magnets being disposed adjacent to each other in repelling relation, an electromagnet pole magnetically connected with each of said stationary magnets intermediate its two poles, a stationary electrical contact member, and a movable electrical contact member operatively connected to said pivoted magnet and selectively engageable with said stationary contact member according to the pivotal position of said pivoted magnet.

9. An electric current actuated relay including a pivoted permanent bar magnet pivoted at a point intermediate its two poles, a pair of substantially parallel stationary permanent bar magnets disposed in substantially the same plane as said pivoted magnet, like poles of said pivoted and stationary magnets being disposed adjacent to each other in repelling relation, the pivoting axis of said pivoted magnet being substantially perpendicular to said plane, an electromagnet pole magnetically connected with each of said stationary magnets intermediate its two poles, a stationary electrical contact member, and a movable electrical contact member operatively connected to said pivoted magnet and selectively operatively connectable with said stationary contact member according to the pivotal position of said pivoted magnet.

10. An electric current actuated relay including a pivoted permanent magnet pivoted at a point intermediate its two poles, a pair of stationary permanent magnets disposed on opposite sides of said pivoted magnet, like poles of said pivoted and stationary magnets being disposed adjacent to each other in repelling relation whereby said pivoted magnet will be self-centered, an electromagnet pole of one polarity magnetically connected to one of said stationary magnets intermediate its two poles and an electromagnet pole of the opposite polarity magnetically connected to the other of said stationary magnets intermediate its two poles, a stationary electrical contact member, and a movable electrical contact member operatively connected to said pivoted magnet, said movable contact member being selectively

operatively connectable with said stationary contact member according to the pivotal position of said pivoted magnet.

11. An electric current actuated relay including a pivoted permanent bar magnet pivoted at a point intermediate its two poles, a pair of substantially parallel stationary permanent bar magnets disposed in substantially the same plane as said pivoted magnet on opposite sides of said pivoted magnet, the pivoting axis of said pivoted magnet being substantially perpendicular to said plane, like poles of said pivoted and stationary magnets being disposed adjacent to each other in repelling relation whereby said pivoted magnet will be self-centered, an electromagnet pole magnetically connected with each of said stationary magnets intermediate its two poles, a stationary electrical contact member, and a movable electrical contact member operatively connected to said pivoted magnet, said movable contact member being selectively operatively connectable with said stationary contact member according to the pivotal position of said pivoted magnet.

12. An electric current actuated relay including a pivoted permanent bar magnet pivoted at a point intermediate its two poles, a pair of substantially parallel stationary permanent bar magnets disposed in substantially the same plane as said pivoted magnet on opposite sides of said pivoted magnet, the pivoting axis of said pivoted magnet being substantially perpendicular to said plane, like poles of said pivoted and stationary magnets being disposed adjacent to each other in repelling relation whereby said pivoted magnet will be self-centered, an electromagnet pole of one polarity magnetically connected to one of said stationary magnets intermediate its two poles and an electromagnet pole of the opposite polarity magnetically connected to the other of said stationary magnets intermediate its two poles, a stationary electrical contact member, and a movable electrical contact member operatively connected to said pivoted magnet, said movable contact member being selectively operatively connectable with said stationary contact member according to the pivotal position of said pivoted magnet.
